UNITED STATES PATENT OFFICE.

ROBERT A. COURTNEY, OF WESTMINSTER, MARYLAND.

DESIGN FOR A BOWL.

Application filed December 21, 1923. Serial No. 8,111. Term of patent $3\frac{1}{2}$ years.

To all whom it may concern:

Be it known that I, ROBERT A. COURTNEY, a citizen of the United States, residing at Westminster, in the county of Carroll, State of Maryland, have invented a new, original, and ornamental Design for Bowls, of which the following is a specification, reference being had to the accompanying drawing, shown forming part thereof, in which—

I claim—

The ornamental design for a bowl as shown in Figure 1.

ROBERT A. COURTNEY.
